(57) **CLAIM**

(21) Appl. No.: **29/243,530**

The ornamental design for an apparatus for recognition of biological information, as shown.

(22) Filed: **Nov. 28, 2005**

DESCRIPTION

(30) **Foreign Application Priority Data**

May 31, 2005 (KR) 30-2005-0018017

FIG. 1 is a perspective view of an apparatus for recognition of biological information of the present invention.

(51) **LOC (8) Cl.** **10-04**

FIG. 2 is a front view of an apparatus for recognition of biological information of the present invention.

(52) **U.S. Cl.** **D10/47**

FIG. 3 is a rear view of an apparatus for recognition of biological information of the present invention.

(58) **Field of Classification Search** D10/47;
118/31.5, 244, 260, 263, 268; 257/77, 914;
427/1, 145, 248.1, 429

FIG. 4 is a left side view of an apparatus for recognition of biological information of the present invention.

See application file for complete search history.

FIG. 5 is a right side view of an apparatus for recognition of biological information of the present invention.

(56) **References Cited**

FIG. 6 is a plan view of an apparatus for recognition of biological information of the present invention; and,
